UNITED STATES PATENT OFFICE.

FITZ R. LONGSTREET, OF GAINESVILLE, GEORGIA.

WINDOW-SHADE.

No. 926,200.

Specification of Letters Patent.

Patented June 29, 1909.

Application filed April 8, 1908. Serial No. 425,925.

To all whom it may concern:

Be it known that I, FITZ RANDOLPH LONGSTREET, a citizen of the United States, residing at Gainesville, Hall county, Georgia, 5 have invented an Improved Shade for Windows.

My invention consists in an improvement for opaque shades, which when used for rendering a room darkened, or private, is so 10 constructed as to admit if desired at the same time during the day, sufficient light for dressing purposes, or for ventilating sleeping apartments at night.

The attached drawings are used to demonstrate my improvement in which—

Figure #1 and Fig. #2 illustrate shades constructed according to my claim.

C D H in both figures represent the window casing, A, the opaque surface of shade, 20 and B B an open work used to connect the shade with roller "e" "f".

In order to obtain the advantages mentioned above, the opaque surface of shade marked "A" in drawings, should be made 25 just long enough to cover window lights effectually; then leaving the warps of shade unwoven or extended at upper or top end to a desired length; these warps to be gathered into cords and said cords made into a wide 30 open work of parallel construction, so as to freely admit both light and air, as shown at

B B Fig. #1; or to obtain the same results, the extended warp of suitable length can be gathered into cords and said cords made into 35 an open work of net construction with wide mesh so as to freely admit light and air as shown at B B Fig. #2. The warp strands are shown at g, g; being gathered into cords B B which are attached to rollers "e" "f".

40 The opaque surface of shade is of suf-

ficient length to cover the lights thoroughly and darken the room; then by simply depressing the shade still further, the open work at the top becomes effective, admitting more and more light as it is pulled down, 45 while the lower or opaque surface cuts off the view, thus rendering the room private.

The application of the extended warp for making the open-work at the top, renders the whole shade more compact and stronger 50 than any other construction, and taking less material can be made economically, and by fastening the cords of the open work to the rollers instead of shade itself, does away with the constant ripping and tearing of shade as 55 from tacks &c.

The benefit of this open construction is two-fold: First: In the day time when there is too much light for office or other work, or when one wishes to make a room private, 60 yet having ample light for dressing &c, simply pull down the shade until as much light is admitted at the top as desired. Second: To insure perfect ventilation and privacy for sleeping apartments pull down the windows 65 at the top, then adjust the open work at top of shade adjacent, so as to freely admit air. This gives perfect ventilation and owing to the mesh construction, the interior of room is not visible from the outside even from a 70 higher view.

Therefore I claim:

A window shade having the warp at upper end extended and said warp gathered and made into an open work for admitting light 75 and air, as set forth.

FITZ R. LONGSTREET.

HENRY E. CORCORAN.

It is hereby certified that in Letters Patent No. 926,200, granted June 29, 1909, upon the application of Fitz R. Longstreet, of Gainesville, Georgia, for an improvement in "Window-Shades," an error appears requiring correction as follows: In the drawings, Figs. 1 and 2, the reference letter *g* should appear to indicate the warp strands, as referred to in the specification; and that the drawings should be read as herein set forth that the same may conform to the record of the case in the Patent Office.

Signed and sealed this 28th day of September, A. D., 1909.

[SEAL.]

C. C. BILLINGS,

Acting Commissioner of Patents.
